CLAIM

What is claimed is the ornamental design for a shipping container, as shown and described.

DESCRIPTION

FIG. 1 is a top, front, left perspective view of a shipping container;

FIG. 2 is a bottom, right, back perspective view thereof;

FIG. 3 is a bottom, right, back isometric view thereof;

FIG. 4 is a top plan view thereof;

FIG. 5 is a front elevational view, with the opposite side being a mirror image thereof;

FIG. 6 is a left side elevational view, with the opposite side being a mirror image thereof; and,

FIG. 7 is a bottom plan view thereof.

1 Claim, 7 Drawing Sheets
